UNITED STATES PATENT OFFICE.

LANDRUM EARL BAGWELL, OF DRAYTON, AND DAVID C. JONES, OF GREENVILLE, SOUTH CAROLINA, ASSIGNEES TO CROMPTON & KNOWLES LOOM WORKS, OF WORCESTER, MASSACHUSETTS, A CORPORATION OF MASSACHUSETTS.

MULTIPLIER FOR LOOMS.

Application filed July 14, 1924. Serial No. 725,773.

To all whom it may concern:

Be it known that we, LANDRUM E. BAGWELL and DAVID C. JONES, said BAGWELL residing at Drayton, county of Spartanburg, State of South Carolina, said JONES residing at Greenville, county of Greenville, State of South Carolina, citizens of the United States, have invented a new and useful Multiplier for Looms, of which the following is a specification.

This invention relates to pattern mechanism for looms and more particularly to multipliers for such mechanism.

In weaving such fabrics as handkerchiefs which have a body of one weave and a border of a second weave, it is desirable to weave the body, which may be a plain weave, with a single bar of pattern chain and the border, which may be fancy, with a comparatively short pattern chain controlled by multiplier mechanism. On the so-called "double-index" dobby it is possible to weave the body of the fabric with the pattern chain stationary, the chain being started in motion when the border is reached by means of a multiplier or pick counter.

Our invention relates more particularly to a pattern mechanism having multiplying, controlling, counting and driving elements on the same shaft with the pattern cylinder.

Another object of our invention is to provide a multiplier with a pair of removable discs which may be replaced by other discs of different sizes so that the factor by which the mechanism multiplies may be varied as desired, the motion transmitting device interposed between the discs being movable to cooperate with various sizes of discs.

A still further object of our invention is to provide a convenient hand control for the multiplier by means of which the latter may be disconnected from the driving portion of the loom and actuated manually.

With these and other objects in view which will appear as the description proceeds, our invention resides in the combination and arrangement of parts hereinafter described and set forth in the claims.

Referring to the drawings,

Fig. 1 is an end elevation of the lower portion of a dobby having our invention applied thereto as viewed from the end of the loom,

Fig. 2 is a front elevation of the mechanism shown in Fig. 1, the manual controlling device being shown in section,

Fig. 3 is a detailed perspective of the actuator disc and transmitter,

Fig. 4 is a diagrammatic view showing the relation of the multiplying discs and the teeth of the transmitter by which the driving disc is caused to actuate the driven disc intermittently, and

Fig. 5 is a vertical section on line 5—5 of Fig. 2.

Referring more particularly to Figs. 1, 2 and 5 it will be seen that we have provided a dobby having sides 10 to which are bolted stands 11 the lower ends of which are formed as bearings to receive shaft 12. The dobby cylinder 13 is fastened to the shaft 12 and is arranged in the present form of the invention to receive a double index dobby pattern chain.

The driving element of the multiplier comprises a sprocket pinion 14 (see Fig. 2) which is fastened by set screw 15 to sleeve 16 extending from a drum 17, the sleeve 16 rotating freely in bearing 18 and being loosely mounted on driving shaft 19 which may extend parallel to the lay of the loom. Located in the drum 17 is a member 20 which is secured to the shaft 19 by set screw 21 and has pivotally mounted thereon hand operated lever 22 one end of which is normally pushed outwardly by compression spring 23 and the other end of which is provided with a handle 24. The periphery of the drum 17 is provided with a notch 25 which normally receives a portion of lever 22. During the normal operation of the loom constantly driven mechanism not shown drives pinion 14 and through the mechanism described rotates shaft 19 every second pick.

As seen in Fig. 2 shaft 19 passes through a bearing 27 and has secured thereto a worm 28 which always meshes with worm gear 29 mounted on shaft 12. As shown in Fig. 5 the hub of the worm gear 29 is extended as at 30 and has secured thereto actuator disc 31. Slidably mounted on shaft 12 is a clutch member 32 having a groove 33 therein to receive the fingers of a clutch arm 34. Lugs 35 extend from the member 32 through 105 a guide 36 fastened to shaft 12 and are so

placed as to be movable into operative relationship with lugs 37 formed on worm gear 29.

The multiplying element of the device 5 comprises a multiplying disc 38 provided with teeth 39 which are preferably double the number of the factor by which the mechanism multiplies the rotation of shaft 19. As seen in Fig. 3 the actuating disc 31 is provided with a pair of teeth 40 which extend laterally beyond an annular run 41 preferably formed integral with the disc 31. The discs are caused to move in unison periodically by a transmitter 42 mounted on the 10 lower end of an arm 43 adjustably fastened to rod 44 fastened to the dobby frame. As shown herein the transmitter is provided with six teeth, alternate teeth being of full width, as indicated at 45 in Fig. 3 and the 15 intermediate teeth being shorter, as indicated at 46.

The transmitter and actuating disc are shown in an intermediate position in Fig. 3 where it will be seen that the axis 47 of the 20 transmitter is so placed with respect to the shaft 12 that two of the long teeth 45 engage the annular run 41 on opposite sides of the axis 47 so as to prevent rotation of the transmitter in either direction and that one of the shorter teeth 46 extends into the path of the advancing lug 40. The lugs 40 are spaced far enough apart to receive the long teeth of the transmitter 42.

The controlling and counting elements of 25 the multiplier comprise a sprocket 48 which receives a pattern chain 49 and is fastened to the multiplying disc 38 so as to rotate therewith. Pivotally mounted on rod 44 is a lever 50 the free end of which extends over 30 the chain 49 in position to be lifted by a ball 51 on the chain against the action of spring 52 interposed between a collar 53 on the rod 44 and said lever. Extending upwardly from the lever 50 is an arm 55 having secured thereto a stud 56 movable freely in a slot 57 formed in lever 58 which is pivoted at 59 to an arm 60 adjustably secured to the rod 44. The other end of lever 58 is slotted as at 61 to receive a bolt 62 carried by the 45 clutch arm 34 and by means of which the position of the latter may be adjusted.

Under normal operation, with the hand lever 22 as shown in Fig. 2 and the clutch member 32 disengaged, as shown in Fig. 5, 50 the shaft 19 will rotate once for every second pick of the loom and worm gear 29 with the actuator disc will rotate idly until one of the lugs 40 engages the tooth 46 extending into the path thereof. The transmitter 42 will then be given a partial rotation and one of the teeth 45 will come between the lugs 40, the teeth of the transmitter 42 at the same time being in mesh with the teeth 39 of the multiplying disc. As the actuator 55 disc 31 continues to rotate the transmitter

42 finishes its motion, having passed through one-third of a revolution. The motion imparted to the multiplier disc moves the pattern chain 49 through one space and this operation will continue until ball 51 lifts lever 50, at which time the latter will be raised to swing the lever 58 in a counter-clockwise direction and the clutch arm 34 will move the lugs 35 into the path of the lugs 27. As the worm gear 29 continues to rotate, shaft 12 will move and the remaining bars of the dobby chain will be brought successively to position to weave the border of the fabric. It will be understood that as long as lever 50 is in its lower position the lugs 35 of the clutch member 32 will be out of contact with the lugs 27 so that shaft 12 remains at rest with one of the bars of the dobby chain under the fingers. This bar may be pegged so as to produce a plain weave. 60

The actuating disc will continue to rotate and cause the intermittent motion of the multiplying disc so that the multiplier chain will move with the pattern chain. When the end of the border has been reached, which will be indicated by the last of the balls 51, the lever 50 will descend and the clutch member 32 will be moved out of driving contact with the worm gear 29. This change occurs as the bar in which the plain 65 weave is to be produced again comes under the dobby fingers. Thus it will be seen that the disk 38 multiplies the rotation of shaft 19 and the chain 49 counts the multiplications, the product of the factor, in this instance eight, and the number of bars in chain 49 equalling the rotations of shaft 19 which occur while the border is being woven. 70

It will be observed that both actuating and the multiplying discs are readily removable so that the same may be replaced by other discs having a greater or lesser multiplying factor and that the arm 43, being adjustably movable about rod 44, can be moved so that the transmitter 42 can be 75 properly placed for all sizes of discs. 105

When it is desired to operate the mechanism by hand the handle 24 of the lever 22, as shown in Fig. 2, will be moved to draw the said lever from notch 25 after which 110 the shaft 19 can be rotated independently of the sprocket 14 and the drum 17. It is desirable to be able to do this where it is necessary to correct a mispick of the loom. 115

From the foregoing it will be seen that I 120 have provided a multiplier having driving, multiplying, counting and controlling elements all on the same shaft and so arranged that the factor by which the multiplying is accomplished may be varied by interchanging the discs and altering the position of the transmitter. Also the device may be disconnected from the loom so as to be operable 125 manually.

Having thus described our invention it will 130

be apparent that changes and modifications may be made therein by those skilled in the art without departing from the spirit and scope of the invention and we do not wish 5 to be limited to the details disclosed herein but what we claim is:

1. In pattern mechanism for looms, a pattern chain cylinder, an actuating disc having a regular motion, a multiplying disc, a 10 transmitter cooperating with the discs to cause both discs to move in unison periodically, mechanism movable to cause the pattern chain cylinder to move with the actuating disc, and means controlled by the 15 multiplying disc to move said mechanism to cause the pattern chain cylinder to move with the actuating disc.
2. In pattern mechanism for looms, a pattern chain cylinder, an actuating disc receiving a regular motion, a multiplying disc, a 20 transmitter cooperating with the discs to effect temporary joint motion of the discs, means to support said transmitter to permit bodily movement thereof with respect to the discs, and means controlled by the multiplying disc to connect the pattern chain cylinder with the regularly moving actuating disc.
3. In pattern mechanism for looms, a pattern chain cylinder, an actuating disc having a regular motion, a multiplying disc movable concentrically with the actuating disc, a pair of lugs extending from the actuating disc, teeth formed on the multiplying disc, a mutilated pinion having certain teeth longer than others and operatively associated with the discs and having all the teeth thereof arranged to mesh with the

teeth of the multiplier disc and having the shorter teeth thereof arranged to mesh 40 with the lugs of the actuating disc periodically, and means controlled by the multiplying disc to cause the pattern chain cylinder and the actuating disc to move in unison.

4. In pattern mechanism for looms, an 45 actuator disc having a regular motion, a multiplying disc, and a transmitter cooperating with the discs and having a portion in operative relationship with the multiplying disc at all times and having another portion 50 which is operatively associated with the actuating disc periodically to cause a periodic joint movement of the discs in unison.

5. In pattern mechanism for looms, a pattern chain cylinder, an actuating disc having a regular motion, a multiplying disc, a transmitter operatively associated with the discs and having a portion always in engagement with the multiplying disc and movable therewith and having another portion 55 normally in engagement with the actuating disc to be held against motion as said actuating disc moves intermittently, said transmitter having other portions to be engaged by said actuating disc to cause a periodic movement of the transmitter and multiplying disc for each complete movement of the actuating disc, and means associated with the multiplying disc to connect the pattern chain cylinder and actuating 60 disc to cause the same to move in unison.

In testimony whereof we have hereunto affixed our signatures.

LANDRUM EARL BAGWELL.
DAVID C. JONES.
